UNITED STATES PATENT OFFICE

119,778

DESIGN FOR A TEXTILE FABRIC

Joseph F. Berlinger, New York, N. Y.

Application January 27, 1940, Serial No. 89,761

Term of patent 3½ years

To all whom it may concern:

Be it known that I, Joseph F. Berlinger, a citizen of the United States of America, residing in city of New York, county of New York, and State of New York, have invented a new, original, and ornamental Design for a Textile Fabric, of which the following is a specification, reference being had to the accompanying drawing, forming part thereof. The single figure on the drawing is a plan view of a textile fabric showing my new design.

The dot and dash lines on the drawing show the design unit which unit is repeated in staggered relation, as indicated by the angles A and A'.

I claim:

The ornamental design for a textile fabric, substantially as shown and described.

JOSEPH F. BERLINGER.
